NECK-BAND CLAMP FOR LAUNDRY
PRESSES

Stanley Marvin, San Francisco, Calif., assignor, by
mesne assignments, to B. E. Witkin, Oakland,
Calif.

Application February 20, 1937, Serial No. 126,859

6 Claims. (Cl. 38—13)

This invention relates to laundry presses as used for pressing or pressure ironing of shirts, and the principal object of the invention is to provide an improved manually operated clamp for holding the neck-band of the shirt at one end of the pressing buck. A further object is to provide such a clamp device which may be operated by one hand. Another object is a clamp of this kind which will automatically grip the neck-band of the shirt when the handle of the clamp is given a short movement and be entirely out of the way when released so as not to interfere with the placing or removal of shirts in pressing or ironing the same.

Other features and advantages of the invention will appear in the following description and accompanying drawings.

In the drawings:

Figure 1 is a side elevation of my improved neck-band clamp with the clamping strap in neck-band gripping position;

Figure 2 is a view similar to that of Figure 1, but shown in vertical central section;

Figure 3 is a vertical central section of the device in open or released position;

Figure 4 is a plan view of Figure 1;

Figure 5 is a front elevation of Figure 1.

Before describing the drawings in detail, it may be said that the type of laundry press with which my invention is particularly adapted has a lower "buck" over which the shirt to be pressed or ironed is stretched, and an upper buck which comes down when the press is closed to tightly press the garment. Either one or both bucks are heated to effect the required "ironing" of the garment.

In the drawings a portion only of the lower buck is shown in dotted lines at 1 and at the end of which my neck-band clamp device is secured.

The device comprises a base member 2 secured as by bolts 3 to the buck and provided with an upstanding flange 4 formed to receive around it the neck band 5 of a shirt 6 when the bosom 7 of the shirt is on top of the buck and the back 8 of the shirt hangs under the buck. The flange preferably has a gap in it at 9 (as shown in Figures 4 and 5) to facilitate placing the neck-band with the fingers, and also an upstanding wire loop 10 in front to function as a support for the collars 11 of collar-attached shirts, which are turned up when placed on the press as indicated by the dotted lines.

The base member 4 is formed with an upwardly extending bracket portion 12 having two arms

13 to which the strap head 14 is pivoted on a horizontal shaft 15. This shaft 15 is secured against rotation in the arms 13 as by pins 16 and carries a spur pinion 17 keyed or otherwise secured thereto and positioned within the side walls of the head 14 which forms a protective housing therefor.

Extending loosely through the head and through two bosses 18 formed on the outsides thereof parallel to shaft 15 is another shaft 19 which has keyed to it another pinion 20 in mesh with pinion 17, while secured to the shaft 19 or to the sides of pinions 20 are two flat lever arms 21 joined at their free ends by a pin 22, which, when the head is rotated on pivot 15 from the position of Figure 3 to that of Figure 2, swings this pin 22 with a faster motion downward to the right to engage into an open ended slot 23 in a pivotally mounted latch 24 which automatically springs over a center to hold pin 22 and the head 14 down in position shown in Figure 2.

Latch 24 is pinned to a shaft 25 which is revolvably supported in arms 13 and has a pair of short upwardly projecting levers 26 pinned to its ends which are engaged at their outer ends each by a coiled tension spring 27, the lower end of which is hooked to a boss 28 on the base 2.

At the upper end of the head 14 is a handle 29 which is swung through a 90° curve in operating the device, or from position of Figure 3 to that of Figure 2, and secured to the outer ends of shaft 19 are rigid arms 30 carrying at their ends a strap 31. This strap is preferably of thin metal and is formed to fit around the forward curved portion of the flange 4 and clamp the shirt neck-band thereagainst when handle 29 is pushed over to the right as shown in Figure 2, and swing upward out of the way when the handle is pushed over to the left as shown in Figure 3.

It will be noted that though the handle is moved but about 90° of arc, the strap has swung from the horizontal against the neck-band (Figure 2) again to the horizontal above the handle (Figure 3) or through an arc of 180°. This is due to the action of spur gear 20 rolling around fixed gear 17.

When the strap is down and engaging the outside of the neck-band as shown in Figure 2, it is evident that since it arrived at that position by swinging down around the axis of shaft 19 as it rolls around shaft 15, through the action of the gears, anything tending to swing it still further down will also force it toward the flange 4 and thus clamp the neck-band more firmly. To au-

automatically effect such further tightening of the clamping strap is the function of the slotted latch 24.

Latch 24 in position shown in Figure 3 is being resiliently urged to turn to the right, as springs 27 are pulling to the right of axis 25, but the latch is prevented from turning as its lower end 24' is stopped by bracket wall 12. However, when the head 14 is swung over toward the right 10 pin 22 enters slot 23 and forces latch 24 to the left, together with levers 26, thus carrying the upper ends of springs 27 to the left of pin 25 so that the pull of the springs is transferred to the left of the pin and tends to urge lever arms 21 still 15 further down, and thus resiliently hold the strap in clamping position, without the necessity of the operator holding onto the handle, so that he may then use both hands in stretching the shirt bosom over the buck and smoothing it out preparatory to 20 closing down the upper buck to press it.

In releasing the neck-band clamping device, a slight leftward push of the handle reverses the position of springs 27 so that it moves with substantially no effort to position 3, bringing its rear edge 14' against a stop rib or lug 32 on bracket 25 sides or arms 13.

From the above description the construction and operation of my improved neck-band clamp should be clearly understood by those skilled in 30 the art and its advantages realized. A feature of particular importance is that the device is relatively very small so that the shirt neck easily goes over it in putting on or taking off the shirts. In Figure 3 between the shirt and the buck is 35 indicated the usual padding 33 used on the bucks in this work.

Having thus described my invention, and its manner of operation, what I claim is:

1. In a laundry press, a shirt neck-band clamping device comprising a base portion adapted to be secured to a press buck and provided with an upstanding flange formed to receive the neck-band, a strap formed to embrace the outer side of the neck-band for clamping it to the flange, an 40 upwardly extending bracket on said base portion, a head portion pivoted on a horizontal axis to said bracket and provided with an operating handle, a shaft carried by said head portion and to which said strap is secured, and cooperating 45 means carried by said head and base portion arranged and adapted to swing said strap into and out of clamping position at a higher angular velocity than that of the head when the head is swung.

2. In a laundry press, a shirt neck-band clamping device comprising a base portion adapted to be secured to a press buck and provided with an upstanding flange formed to receive the neck-band, a strap formed to embrace the outer side 50 of the neck-band for clamping it to the flange,

an upwardly extending bracket on said base portion, a head portion pivoted on a horizontal axis to said bracket and provided with an operating handle, a shaft carried by said head portion and to which said strap is operatively connected, and 5 cooperating gear means carried by said head and base arranged and adapted to swing said strap into and out of clamping position at a higher angular velocity than that of said head when the head is swung.

3. In a laundry press, a shirt neck-band clamping device comprising a base portion adapted to be secured to a press buck and provided with an upstanding flange formed to receive the neck-band, a strap formed to embrace the outer side of 15 the neck-band for clamping it to the flange, an upwardly extending bracket on said base portion, a head portion pivoted on a horizontal axis to said bracket and provided with an operating handle, a shaft carried by said head portion, arms extending from the ends of said shaft and to which said strap is secured, and cooperating planetary gear means carried by said head and base arranged and adapted to swing said strap into and out of clamping position at a higher angular velocity 20 than that of said head when the head is swung.

4. In a construction as specified in claim 3, resilient retaining means adapted and arranged to engage said head and force it toward clamping position.

5. In a construction as specified in claim 3, resilient retaining means adapted and arranged to engage said head and force it to clamping position, during motion of said head toward the buck and to yieldingly allow the release of said head 35 as the head is swung toward released position.

6. In a shirt neck-band clamp of the character described, a hand operated head mounted to swing in an arc in a vertical plane, means mounting a clamping strap for swinging with the head to 40 clamping and released positions with respect to a cooperating neck-band form fastened to a pressing buck, and spring toggle means adapted and arranged to engage the strap mounting means and resiliently force said strap to clamping position said spring toggle means including a lever pivotally mounted with respect to said neck band form, cooperating means operatively connected with said head and said lever and consisting of a projection operatively associated with one, and a slotted member operatively associated with the other, and stop means to limit the motion of said lever away from an engaging position to a position substantially tangent to the arcuate path of said cooperating means associated with the head, 55 said spring toggle being arranged and adapted to have its dead center position lie between said substantially tangent position and a position in which the neck band engages said form.
